United States Patent Office

Des. 222,078

Patented Sept. 28, 1971

222,078

SHELF BRACKET ASSEMBLY

Louis G. Bobrowski, Berlin, Conn., assignor to The Stanley Works, New Britain, Conn.

Filed Dec. 5, 1969, Ser. No. 20,383

Term of patent 14 years

Int. Cl. D6—99

U.S. Cl. D33—3

FIG. 2

FIG. 1

FIG. 3

FIG. 1 is a perspective view of a shelf bracket assembly showing my new design;

FIG. 2 is a top plan view thereof;

FIG. 3 is a side elevational view thereof;

I claim:

The ornamental design for a shelf bracket assembly, as shown.
